FUEL INJECTOR

Louis O. French, Milwaukee, Wis., assignor to
Ethel Quarles French, Milwaukee, Wis.

Application February 23, 1937, Serial No. 127,185

12 Claims. (Cl. 299—107.2)

The invention relates to fuel injectors for internal combustion engines and more particularly to injectors of the fuel metering type. One of the objects of the invention is to provide a fuel metering injector in which the pump plunger has a constant stroke and works in a barrel whose outer end acts as an outwardly opening discharge valve to control the supply of fuel to a nozzle member which in certain instances cooperates directly therewith to determine the spray characteristics. With the present invention the valve is protected from the direct heat of the engine and permits of the efficient distribution of fuel to nozzles of single or multiple jet form. More particularly also the pump barrel is arranged to be turned on a fixed seat during the operation of the engine so that the valve will be kept clean, thus eliminating frequent inspections and the necessity for grinding the discharge valve. In the preferred form of the invention the pump barrel is turned during each operation of the pump plunger, and a portion of this turning may occur while the valve end of the barrel is on its seat. Also in those applications to engines where a single cone-shaped spray is used the injector has been greatly simplified in that the valved end of the barrel cooperates with a nozzle plate to determine in general the spray characteristics, said plate also acting as a spring to hold the barrel on its seat, the valve end of the barrel being grooved and the plate having a relatively large hole or orifice so that if the injector should tend to clog the hole in the plate may be cleaned out with a pin or piece of wood and the abutting surfaces of the plate and barrel wiped off, thus permitting the injector to be serviced while in the field.

A further object of the invention is to provide a fuel metering injector in which the pump plunger works in a barrel whose outer end acts as an outwardly opening discharge valve, said barrel being normally held against its seat by an apertured resilient plate associated with a fixed nozzle member so that the fuel is delivered between the head of the valve and said plate to said nozzle member without greatly reducing its pressure after leaving the valve; the plate also simplifying the assembly of the barrel in the casing and permitting of the use of a stepped one piece casing if desired.

The invention further consists in the several features hereinafter set forth and more particularly defined by claims at the conclusion hereof.

Referring to the drawing:

Fig. 1 is a side elevation view of a device embodying the invention;

Fig. 2 is a transverse sectional view on an enlarged scale taken on the line 2—2 of Fig. 1 with the plunger shown in full in its inner position;

Fig. 3 is a detail reduced size sectional view taken on the line 3—3 of Fig. 2;

Fig. 4 is a detail reduced size sectional view taken on the line 4—4 of Fig. 2;

Fig. 5 is a detail reduced size sectional view taken on the line 5—5 of Fig. 2;

Fig. 6 is a perspective view of the guide for the rotator;

Fig. 7 is a detail reduced size sectional view taken on the line 7—7 of Fig. 2;

Fig. 8 is an enlarged detail sectional view of the lower end of the injector;

Fig. 9 is a bottom plan view of the lower end of the pump barrel, parts being broken away;

Fig. 10 is a detail sectional view of an injector showing certain modifications;

Fig. 11 is a detail reduced size sectional view taken on the line 11—11 of Fig. 10;

Fig. 12 is a detail view showing a development of a part of the pump barrel shown in Fig. 10;

Fig. 13 is a detail reduced size sectional view taken on the line 13—13 of Fig. 10;

Fig. 14 is a view similar to Fig. 8 showing certain modifications.

Referring to Figs. 1 to 9 of the drawing, the numeral 16 designates a casing, 17 a pump barrel, 18 a pump plunger working in said barrel, 19 a rotator, 20 a guide for said rotator, 21 pins on said guide, 22 a control sleeve slidably keyed on said casing and cooperating with said pins, 23 a nozzle plate, 24 a casing member having threaded engagement with the casing 16 and flanged to clamp the plate 23 between it and the end of the casing, 25 the follower or guide for the plunger, and 26 a return spring for the plunger interposed between the casing and the flanged top of said follower.

The casing 16 is a tubular member having stepped bores 27 and 28 extending lengthwise thereof with a recessed valve seat 29 formed at the lower end of the bore 28, a spring seat shoulder 30 at the upper end thereof, oppositely disposed straight slots 31 in which the pins 21 work, and spaced ports 32 and 33 connected by flats or channels 34 and 35 with passages 36 and 37 leading from the threaded bores 27 and 28 in the casing member 24.

The barrel 17 is a tubular member rotatably and slidably mounted in the bore 28 and having a valve flange 40 at its lower end seating on the

seat 29, a centrally disposed bore 41 in which the plunger works, ports 42 and 43 adapted to register with the ports 32 and 33 and an annular recess 44 adjacent the flange 40. The lower end 5 of the barrel is closed off either by an integral part thereof or preferably to facilitate finishing operations on the bore 41 by a plug 45 having a tapered drive fit with the tapered outer end of the bore 41, and passages connect the interior 10 of the bore 41 with the recess 44; these passages being formed by a transverse bore 46 through the barrel and plug and a bore 47 in said plug intersecting the bore 46. The upper end of the barrel is provided with oppositely disposed spirally inclined slots 48 which may also have an idle 15 straight portion 49.

The rotator 19 is a tubular member slidably and rotatably mounted in the bore 21 and carrying oppositely disposed pins 50 at its lower end 20 working in the slots 48 and having concentric bores 51 and 52 and oppositely disposed key slots 53.

The guide 20 for the rotator is a tubular member rotatably mounted in the bore 21 and having a central bore 54 and diametrically disposed legs 25 or key portions 55 slidably fitting the key slots 53.

The plunger 18 works in the bore 41, has a stop flange 56 intermediate its ends, and its upper end is in threaded engagement with the follower 30 25 to which it is locked by a lock nut 57 whose lower end forms a stop flange.

The control sleeve 22 is slidably mounted on the casing 16, carries a key 58 working in a lengthwise extending keyway 59 in said casing, 35 has diametrically disposed spirally inclined slots 60 through which the ends of the pins 21 project and has an annular groove 61 to receive the ends of a shifter fork (not shown) which may be manually or governor operated.

40 The discharge valve end of the injector is yieldingly held to its seat by a spring here shown in the form of a flat steel or suitable alloy metal disk or plate 23 having the spray opening 62 therein which is relatively large, for example two 45 to three hundredths of an inch in diameter. This plate bears against the plug portion of the valve head end of the barrel which portion projects slightly beyond the other parts of the head so as to provide a slight clearance, indicated at 63, 50 between the barrel and the plate and so that when the parts are clamped together by the screwing up of the casing member 24 on the casing 16, the spring or plate 23 is put under a pre-determined tension. Passages are provided 55 between the plate 23 and the plug 45 here shown as tangentially disposed grooves 64 connecting the space 63 with a centrally disposed recess 65, which construction produces a wide angle whirling spray, but other grooving may be used to produce 60 other forms of spray, and the plate 23 may carry a centrally disposed nozzle member provided with a plurality of holes, or the discharge arrangements hereinafter described and shown at the lower end of Fig. 10 and in Fig. 14 may be used 65 with the oscillatory pump barrel 17.

With this construction when the plunger 18 is in its lowest position, the barrel 17 has been turned to bring the port 42 into register with the port 32, and fuel flows through these ports 70 and connecting passages 34, 36 and 38 from the supply or overflow source into the pump chamber either under gravity or pressure head and under the suction effect of the plunger as said plunger moves upwardly until the piston uncovers 75 the port or ports 43, and thereafter fuel continues

to flow into the chamber from the supply or an overflow source, through the port or ports 43. The plunger continues to move upwardly above the ports 43 to the dotted line position X, and during this time the stop 56 which has engaged 5 the rotator 19 moves the same upwardly in the guide 20, and as it does so, the pins 50 traveling along the slots 48 act to turn the barrel 17 clockwise as viewed in Fig. 5 to move the port 42 to a lapped position out of register with the 10 port 32. Thereafter, the plunger starts on its downstroke, and in moving from the dotted line position to a position adjacent the ports 43 any air or excess fuel is forced out of the pump chamber through said ports to the supply or overflow 15 connection, and then after the plunger has covered the ports 43, the pressure in the pump chamber rises to a point where it overcomes the spring tension exerted by the plate on the lower end of the barrel and by the gases in the engine also 20 acting on the lower end of the barrel, and the valved end 40 of the barrel moves slightly off its seat 29, and delivery through the passages 47, 46 around the head of the valve, clearance 63, 25 grooves 64 to the opening 62 starts. During this time the lower end of the nut 54 has engaged the top of the rotator 19, and as the plunger continues to move downwardly, the rotator moves with it and through the pins 50 acts to turn the sleeve 17 back to bring the port 42 into register 30 with the port 32, and when this occurs, at some part of the remaining downstroke of the plunger, the pressure in the pump chamber drops, the barrel 17 under the action of its closing spring and the cylinder gases moves back on its seat 29 and delivery ceases, it being noted that a groove 66 on the sleeve connects with the port 42 which groove is of a length to allow by-passing to occur during the entire delivery stroke of the plunger, but whose effect will be varied by the angular 4 relation of the port 42 relative to the port 32. If then the position of the port 42 relative to the port 32 is angularly shifted, these ports will come into register sooner or later depending upon the adjustment which is effected by longitudinally shifting the sleeve 22 relative to the casing 16, and this shifting may also carry the barrel through a no-delivery position to a position in which the recess 66 is on the opposite side of the port 32 from that shown in Fig. 5 in which instance the injection would have a variable beginning during the oscillatory motions of the barrel. In the latter case, the port 42 would communicate with the port 32 during the first part of the downward travel of the plunger 18 after covering the port or ports 43. It is also to be noted that the barrel 17 is being turned on its seat during the time the pressure in the pump chamber is insufficient to move the valved end of the barrel off its seat and that the valved end of the barrel leaves its seat for different periods for different adjustments thereof and thus reseats itself in different positions. Both of these factors tend to keep the seating surfaces wiped clean and from becoming coated with fine foreign matter that may be present in the fuel. It is also to be noted that the turning of the barrel 17 relative to the plate 23 and at its outlet end in contact therewith tends to keep fuel passages at the head end of the barrel from becoming clogged. It is further to be noted that when operating at high speed the turning of the grooved end of the barrel may assist in giving the fuel spray from the grooves 64 a whirling motion. Thus provision is made for assuring the sealing

of the discharge valve end of the injector for long periods of time without inspection and the preventing of the clogging of the spray passages or passages leading thereto which may be relatively large without impairing an efficient spraying action.

Some advantages of the invention may be obtained where the pump barrel is intermittently turned either through the mediation of a governor or the operator, and in Figs. 10 to 13 I have shown an injector which has these advantages. In this modification the numeral 67 designates a casing, 68 a pump barrel, 69 a pump plunger working in said barrel, 70 a gear slidably splined at 70' 10 to the upper end of said barrel and meshing with a rack bar 71 slidably guided in the casing 67, 72 an apertured spring plate, 73 a nozzle member, 74 a casing member having threaded engagement with the casing 67 and flanged to 20 clamp the disk 72 and the member 73 between it and the end of said casing, and 75 a return spring for the plunger interposed between the casing and the flanged top of the plunger following 25 76.

The casing 67 is a tubular member having stepped bores 77 and 78 extending lengthwise thereof with a recessed valve seat 79 formed at the lower end of the bore 78, and spaced ports 80 and 81 communicating through suitable passages 30 with the supply or overflow connections 82 and 83. The gear 70 rotates in the bore 77 and seats on the shoulder formed between the two bores of said casing and is held against lengthwise movement with respect thereto by a pin 84 mounted 35 in said casing.

The pump barrel is a tubular member rotatably and slidably mounted in the bore 78 and having a valve flange 85 at its lower end seating on the seat 79, a centrally disposed bore 86 in which the 40 plunger works and ports 87 and 88 adapted to register with the ports 81 and 80, and has an angular recess 89 adjacent the flange 85. The lower end of the barrel is closed off as in the first 45 described construction by a plug 90 having a fluid tight fit in the outer end of the bore 86, and passages connect the interior of said bore with the recess 89, these passages being formed by a transverse bore 91 through the barrel and plug and a bore 92 in said plug intersecting the bore 91.

Any suitable metering control arrangement for changing the amount of fuel delivered by the pump by the relative rotation of the pump plunger and barrel may be used, and for illustration 50 I have shown the lower end portion of the pump plunger provided with a transverse bore 93, an over travel relief portion 94 at one end of said bore, and a longitudinally extending bore 95 intersecting the bore 93. The port 88 in the barrel 55 is of triangular form as shown in Fig. 12 so as to form a variable by-pass cooperating with one end of the bore 93 to by-pass fuel from the pump at different portions of the stroke of the plunger depending upon the angular position of the port 60 88 relative to the bore 93.

The discharge valve end of this injector is yieldingly held to its seat by the centrally apertured spring plate 72 which bears adjacent its central opening 96 against the plug portion of the valve head end of the barrel which portion projects slightly beyond the other parts of the head so as to provide a slight clearance indicated at 97 between the barrel and the plate, and so that when said plate and the nozzle member 73 are 75

clamped in position by the member 74, the plate 72 is put under a predetermined tension. A transverse passage 98 formed by a groove in the plug is provided between the plate 72 and the plug 90 to connect the space 97 with opening 96, 5 and the walls of the nozzle member 73 are inclined slightly adjacent the plate to allow the plate to be tensioned and to flex slightly when the valved end of the barrel opens.

The nozzle member 73 is here shown as of the 10 multiple jet type having a central passage 99, whose length may vary to suit the particular engine installation, and whose outer end communicates with the engine cylinder through the spray openings 100. 15

The follower 76 of the plunger is shown as having a splined connection 101 with the upper portion of the bore 77.

With this modified form of construction, as the plunger 69 moves downwardly from its upper position shown in Fig. 10, some of the fuel is by-passed back to the supply through the port 87 because of the elongated relief 94 on the plunger moving past said port. This by-passing permits air to be expelled from the pump chamber, and when the relief 94 passes the port 87, pressure is built up in said chamber and acts against the pressure of the spring 72 and the gases in the cylinder to move the barrel downward to open the valved end thereof and allow fuel to pass around the valve head, and between said head and plate 72 to the opening 96 and the passage and thence through the spray openings to the engine until the port 93 registers with a part of the port 88 to establish connection with the supply or overflow, and the pressure in the pump chamber then drops and the valve end of the barrel reseats itself. Thereafter, the plunger 69 returns to its initial position shown in Fig. 10. Since during the operation of the engine, particularly where the same is operating under variable loads, it is necessary to turn the barrel 67 so as to bring the relief into different positions relative to the port 88, this turning of the valve relative to its seat 79 will help in keeping the seating surfaces clean as compared to a straight reciprocating valve. 30 35 40 45

It is also to be understood that the discharge arrangement of the first construction may be used in this modified form so that the plate 72 alone forms the nozzle member. 50

In Fig. 14 another discharge arrangement is shown in which the rotatable tubular pump barrel 102 may be similar to either the barrel 17 or 68 as regards its metering functions and similarly mounted in a casing 103 similar to either the casing 16 or 67 and having a bore 104 in which the pump plunger works, a valved end 105 seating against the recessed seat 106 and provided with a plug 107 similar to the plugs 45 and 90 except that the lower end thereof is formed into a tapered pintle 108 which projects through an opening 109 in the spring closure plate 110 and cooperates with a bore 111 in the end of the casing member 112 similar to the members 24 or 74 to provide an annular spray orifice. The plate 110 is clamped at its outer edge against the end of the casing 103 by the flanged end of the member 112, this flange 113 sloping slightly to the bore 111. With this construction when the fuel pressure within the pump chamber moves the valved end of the barrel 105 off its seat, the fuel passes from the pump bore through the passages 114 and 115, 70 75

recess 116, past the valve and between the valved head of the barrel and the plate 110, through slots 111 formed in the end of the plug which may be tangentially disposed similar to the slots 64 and then through the passage provided between the pintle 108 and the openings 109 and 111.

It is to be noted in the above constructions that the central portion of the valved end of the 10 barrel is at all times in contact with the spring plate and that the barrel only has a slight longitudinal movement. This contact serves to conduct heat away from the spring plate to prevent its overheating, and where the plug is made separate, it may be made of metal with especially 15 good conducting properties, such as beryllium copper. The other parts heretofore described are made of steel or suitable steel alloys. Since the valved end of the barrel is closely associated 20 with the spring plate, the energy of the outflowing fuel stream will not be materially dissipated before issuing from the spray nozzle. Furthermore, the barrel may on its outward movement 25 contact the spring plate beyond its center and be provided with grooves at these contacting points.

While in the construction shown in Fig. 10 the barrel is turned to different positions to control the metering, it will be appreciated that some of 30 the advantages of the discharge arrangements here shown may be realized where the pump plunger is turned instead of the barrel to regulate the metering.

Reference is here made to my copending applications Serial No. 63,576, filed February 12, 35 1936, for Fuel pump, and Serial No. 107,305, filed October 24, 1936, for Fuel pump for internal combustion engines, for matter shown but not specifically claimed herein.

I desire it to be understood that this invention 40 is not to be limited to any particular form or arrangement of parts except in so far as such limitations are included in the claims.

What I claim as my invention is:

1. In a fuel injector, the combination of a casing 45 having a supply port, a pump barrel mounted to turn and reciprocate in said casing and provided with an inlet port communicating with said supply port and having a closed valved end seating on said casing and controlling the discharge of fuel from said barrel, a plunger reciprocating in said barrel, means to turn said barrel during the operation of the engine, and means to normally hold the valved end of said barrel 50 against its seat.

2. In a fuel injector, the combination of a casing having a supply port, a pump barrel mounted to turn and reciprocate in said casing and provided with an inlet port communicating with said supply port and having a closed valved end 55 seating on said casing and controlling the discharge of fuel from said barrel, a plunger reciprocating in said barrel, means to turn said barrel during the operation of the engine, and an apertured spring plate secured to said casing and bearing against the valved end of said barrel to exert a closing pressure thereon and provide a discharge passage.

3. In a fuel injector, the combination of a casing having a supply port, a pump barrel 70 mounted to turn and reciprocate in said casing and provided with an inlet port communicating with said supply port and having a closed valved end seating on said casing and controlling the discharge of fuel from said barrel, a plunger re-

ciprocating in said barrel, means to turn said barrel during the operation of the engine, a centrally apertured spring plate secured to said casing and bearing against the valved end of said barrel to exert a closing pressure thereon, and a nozzle member having a discharge opening communicating with the aperture in said plate. 5

4. In a fuel injector, the combination of a casing having a supply port, a pump barrel mounted to turn and reciprocate in said casing 10 and provided with an inlet port communicating with said supply port and having a closed valved end seating on said casing and controlling the discharge of fuel from said barrel, a plunger reciprocating in said barrel, means to turn said barrel during the operation of the engine, an apertured spring nozzle member secured to said casing and bearing against the valved end of said barrel to exert a closing pressure thereon and cooperating therewith to determine in general 15 the spray characteristics of said nozzle member.

5. In a fuel injector, the combination of a casing having a supply port, a pump barrel mounted to turn and reciprocate in said casing 20 and provided with an inlet port communicating with said supply port and having a closed valved end seating on said casing and controlling the discharge of fuel from said barrel, a plunger reciprocating in said barrel, means to turn said barrel during the operation of the engine, a centrally apertured spring plate secured to said casing and bearing against the valved end of said barrel to exert a closing pressure thereon, a nozzle member having a discharge opening communicating with the aperture in said plate, and a pin projection on the valved end of said barrel 25 working in said nozzle member and cooperating therewith to control the character of the fuel spray. 35

6. In a fuel injector, the combination of a casing having a supply port, a pump barrel mounted in said casing to reciprocate relative thereto and provided with an inlet port communicating with said supply port and having a closed valved end 45 seating on said casing and controlling the discharge of fuel from the barrel, a plunger reciprocating in said barrel, and a centrally apertured resilient nozzle member secured to said casing and bearing against the valved end of said barrel to exert a closing pressure thereon. 50

7. In a fuel injector, the combination of a casing having a supply port, a pump barrel mounted in said casing to reciprocate relative thereto and provided with an inlet port communicating with said supply port and having a closed valved end seating on said casing and controlling the discharge of fuel from said barrel, a plunger reciprocating in said barrel, a centrally apertured spring plate secured to said casing and bearing against the valved end of said barrel to exert a closing pressure thereon, and a nozzle member having a discharge opening communicating with the aperture in said plate. 55

8. In a fuel injector, the combination of a casing having a supply port, a pump barrel mounted in said casing to reciprocate relative thereto and provided with an inlet port communicating with said supply port and having a closed valved end seating on said casing and controlling the discharge of fuel from said barrel, a plunger reciprocating in said barrel, a centrally apertured spring plate secured to said casing and bearing against the valved end of said barrel to exert a closing pressure thereon, a 65

5 nozzle member having a discharge opening communicating with the aperture in said plate, and a pin projection on the valved end of said barrel working in said nozzle member and cooperating therewith to control the character of the fuel spray.

9. In a fuel injector, the combination of a casing having a supply port, a pump barrel mounted to turn and reciprocate in said casing and provided with an inlet port communicating with said supply port and having a closed valved end seating on said casing and controlling the discharge of fuel from said barrel, a plunger reciprocating in said barrel, means to oscillate said barrel during each cycle of movement of said plunger, and means to normally hold the valved end of said barrel against its seat.

10. In a fuel injector, the combination of a casing having a supply port, a pump barrel mounted to turn and reciprocate in said casing and provided with an inlet port communicating with said supply port and having a closed valved end seating on said casing and controlling the discharge of fuel from said barrel, a plunger reciprocating in said barrel, means to oscillate said barrel during each cycle of movement of said plunger, and a centrally apertured spring plate secured to said casing and bearing against the valved end of said barrel to exert a closing pressure thereon.

11. In a fuel injector, the combination of a

casing having a supply port, a pump barrel mounted to turn and reciprocate in said casing and provided with an inlet port communicating with said supply port and having a closed valved end seating on said casing and controlling the discharge of fuel from said barrel, a plunger reciprocating in said barrel, means to oscillate said barrel during each cycle of movement of said plunger, an apertured spring nozzle member secured to said casing and bearing against the valved end of said barrel to exert a closing pressure thereon and cooperating therewith to determine in general the spray characteristics of said nozzle member.

12. In a fuel injector, the combination of a casing having a supply port, a pump barrel mounted to turn and reciprocate in said casing and provided with an inlet port communicating with said supply port and having a closed valved end seating on said casing and controlling the discharge of fuel from said barrel, a plunger reciprocating in said barrel, means to oscillate said barrel during each cycle of movement of said plunger, a centrally apertured spring plate secured to said casing and bearing against the valved end of said barrel to exert a closing pressure thereon, and a nozzle member having a discharge opening communicating with the aperture in said plate.

LOUIS O. FRENCH. 30
